LIGHTING SYSTEM FOR BEDS

Manuel L. Murrell, Santa Monica, Calif.

Application December 8, 1931, Serial No. 579,773

1 Claim. (Cl. 240—4)

This invention relates to and has for its purpose the provision of a lighting system preferably incorporated in the structure of a bed as a permanent part thereof during manufacture of 5 the bed, and embodying one or more lamps disposed on the head frame of the bed to project light over the bed so that an occupant of the latter will have illumination for reading, while disposed in a comfortable posture, the system 10 including a switch conveniently accessible for manipulation by the occupant to light or extinguish the lamp at will, all without in any manner detracting from the design or appearance of the bed and to the end of dispensing with 15 the present practice of resorting to accessories for this purpose.

Only one form of lighting system for beds embodying this invention will be shown and described and the novel features thereof pointed 20 out in the claim.

In the accompanying drawings:

Figure 1 is a view of the head frame of a bed in front elevation with one form of lighting system embodying this invention, associated 25 therewith;

Figure 2 is an enlarged view of the head frame in rear elevation and embodying the lighting system shown in Figure 1;

Figure 3 is an enlarged vertical sectional view 30 taken on the line 3—3 of Figure 2 and looking in the direction of the arrows;

Figure 4 is an enlarged horizontal sectional view taken on the line 4—4 of Figure 2 and looking in the direction of the arrows;

Figures 5 and 6 are enlarged fragmentary sectional views taken respectively on the lines 5—5 and 6—6 of Figure 2 and looking in the directions of the respective arrows; and

Figure 7 is a view of a different style of head 40 in rear elevation with the lighting system embodying this invention applied thereto.

Referring specifically to the drawings in which similar reference characters designate similar parts in each of the several views, and particularly to Figures 1 to 6 inclusive, this invention in its present embodiment is shown associated with a conventional form of wooden bed the head frame H of which is composed of posts 10, top and bottom rails 11 and 12, and a panel 13 50 spanning the posts and rails. The marginal edges of the panel 13 are received and secured in grooves 14 formed in the confronting sides of the posts and rails; and in the present instance the groove of one post 10 and that portion of the 55 groove of the top rail 11 from its joinder with

the post to approximately its center, are of increased depth to accommodate and confine a pair of suitable conductors 15 so that the latter will be entirely concealed when the parts of the head frame are assembled.

The conductors 15 extend into a pocket 16 formed in the inner side of said post adjacent its lower end, and are connected to a conventional form of socket 17 supported in the pocket and providing terminals for co-action with a detachable plug 18 in supplying current to the conductors from a suitable source of supply through the medium of flexible wiring 19.

The opposite ends of the conductors 15 extend from the groove 14 of the top rail 11 at the vertical center of the panel 13, downwardly along the back of the latter into a shallow cup shaped casing 20 secured to the back of the panel by screws 21 to span an opening 22 formed in the panel. That portion of the conductors 15 between the top rail and casing is concealed in a channel shaped member or extension 23 also secured to the back of the panel.

A lamp socket 24, to the terminals of which the conductors 15 are connected, is supported 25 by the casing 20 in the opening 22 at one end thereof; and mounted in the socket 24 is a lamp 25 also disposed in the opening so that when the lamp is lighted, the light rays emanating therefrom will project forwardly from the panel 30 13 over the bed at a height suitable for an occupant of the bed to read by or utilize for other purposes. Spanning the opening 22 at the front of the panel is a frosted lens 26 held in place by a suitably ornamented frame 27 secured to 35 the panel by screws 28.

A conventional form of rotary switch 29 which is placed in series with the conductors 15 by branch conductors 30, is supported in the casing 20 and is provided with an operating knob 31 40 extending through an opening in the frame 27 so as to be accessible at the front of the panel 13 for manual operation by the occupant of the bed to light or extinguish the lamp 25 at will.

Referring now to Figure 7, it will be noted that 45 in the style of bed herein shown, the panel 13a of the head frame H' is lacking a top rail, and that a bottom rail 12a connects the posts 10a. In this instance the casing 20 is inverted and its channel extension 23 is of increased length to 50 span the space between the bottom of the casing and the bottom rail 12a. The conductors 15 extend from the casing through the extension 23 and are confined in the grooves of the bottom rail and lower portion of one of the posts 55

for connection to a source of current supply in the manner previously described.

It will be manifest that the lighting system above described, can be readily applied at a minimum cost to the head frame of a bed during its manufacture so as to become a permanent part of the head frame and provide a much desired and convenient light for use in reading by the occupant of a bed, all while effectively concealing the wiring and in fact enhancing the appearance of the bed.

I claim:

As a new article of manufacture, a lighting device for use in connection with beds employing a head frame having a panel formed with an opening; and spaced-apart grooved support-

ing posts and a grooved rail connecting the posts with each other and in the groove of the latter and the grooves of the posts, respective edges of the panel are secured, comprising a channel member of a length to extend from the rail to a point entirely across the panel opening at the rear of the panel, and an electric lamp disposed in the opening to reflect light forwardly through the opening and including current supply conductors passing through the channel member and adapted to be run through the grooves between the panel and the posts of the head member and provided with a terminal connector adapted to be exteriorly exposed from one of said posts.

MANUEL L. MURRELL.
